[57] CLAIM

The ornamental design for a miniature spot cleaner, as shown and described.

DESCRIPTION

FIG. 1 is a perspective view of a miniature spot cleaner showing my new design;

FIG. 2 is a right side elevational view thereof;

FIG. 3 is a left side elevational view;

FIG. 4 is a top plan view;

FIG. 5 is a bottom plan view;

FIG. 6 is a rear elevational view; and,

FIG. 7 is a front elevational view.

The electric cord and hose shown in all views are understood to represent indeterminate length.
